CLAIM

The ornamental design for a mask for horses, as shown and described.

DESCRIPTION

FIG. 1 is a first perspective view of a mask for horses showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1; and,

FIG. 10 is an enlarged view of the selected portion in FIG. 1.

The broken lines shown in the drawings depict portions of the mask for horses in which the design is embodied that form no part of the claimed design. The long-dash short-dash lines in FIG. 1 are for the purpose of depicting the boundary lines of the enlarged views of FIGS. 9 and 10, and form no part of the claimed design.
